UNITED STATES PATENT OFFICE.

SAMUEL WILDE, OF WILLIAMS, CALIFORNIA.

HEEL FOR BOOTS OR SHOES.

SPECIFICATION forming part of Letters Patent No. 285,194, dated September 18, 1883.

Application filed December 19, 1882. (No model.)

To all whom it may concern:

Be it known that I, SAMUEL WILDE, of Williams, in the county of Colusa and State of California, have invented a new and Improved Boot or Shoe Heel, of which the following is a full, clear, and exact description.

The object of the invention is to make a low heel independent of and readily attachable to the boot or shoe, as hereinafter described.

Figure 1 of the drawings is a view in perspective of my improved heel. Fig. 2 is a longitudinal vertical section, and Fig. 3 a vertical cross-section.

In the drawings, A represents a seamless shell of sole-leather. B is the bottom plate, which is attached by tacks or screws to the lower edge of the shell. C is the filling, which preferably consists of waste scraps mixed with glue and pressed into the shell, so as to fill the

cavity. D is the top concaved cap, which receives the correspondingly-shaped heel-bottom of the shoe, and is fastened thereto by the ordinary double-pointed tacks or the common channel-tacks. The latter pass through 25 the stiffener into the insole and are clinched.

I thus form a heel adapted to nailed, pegged, or machine-made boots or shoes. My heel is simple, inexpensive, and easily applied.

What I claim as new and of my invention 30 is—

A boot or shoe heel formed of the seamless leather shell A, the bottomlift, B, the filling C, and the top concaved cap, D, as shown and described.

SAMUEL WILDE.
